UNITED STATES PATENT OFFICE.

JAMES M. PURDY, OF NEW YORK, N. Y., ASSIGNOR TO FREDERICK E. TEVES, OF GLEN COVE, NEW YORK.

CAN-OPENER.

1,076,231.

Specification of Letters Patent. Patented Oct. 21, 1913.

Application filed March 19, 1912. Serial No. 684,711.

To all whom it may concern:

Be it known that I, JAMES M. PURDY, a citizen of the United States, and residing at New York, in the county of New York and State of New York, have invented certain new and useful Improvements in Can-Openers, of which the following is a specification, such as will enable those skilled in the art to which it appertains to make and use the same.

This invention relates to devices for opening cans, and the object thereof is to provide an improved device of this class designed particularly to open cans containing liquid substances, such as, sterilized milk, condensed milk, soups and liquid products of any kind or class, a further object being to provide a can opener of the class and for the purpose specified, which is simple in construction and comparatively inexpensive, and which may be easily manipulated; and with these and other objects in view the invention consists in a device of the class specified constructed as hereinafter described and claimed.

The invention is fully disclosed in the following specification of which the accompanying drawing forms a part, in which the separate parts of my invention are designated by suitable reference characters in each of the views, and in which:

Figure 1 is a side view of a can the top portion of which is shown in section, and showing also one form of my improved can opener, and one step in the operation thereof;—Fig. 2 a view similar to Fig. 1 and showing another step in the operation of the can opener;—Fig. 3 a plan view of the can and showing the result produced by the first step in the operation of the opener;—Fig. 4 a view similar to Fig. 3 but showing the result produced by the second step in the operation of the opener and Fig. 5 a bottom plan view of the opener.

In the accompanying drawing I have shown at *a* a can of the class usually employed as containers for various kinds and classes of food products in liquid form, and in the practice of my invention, I provide a can opener comprising an oblong body part *b* which may be slightly wider at one end than at the other, and the end portion *b*² of which forms a handle for the manipulation of the device.

The body or handle *b* is provided opposite the end portion *b*² thereof with a blade *c* which projects therefrom at right angles thereto, and said blade comprises a penetrating point and forwardly curved side portions having cutting edges which taper from the point toward, and gradually increase in width, to the body or handle; and the forwardly directed curve of the side portions of the blade is such as to make said blade approximately semi-circular in cross section at its widest point, and the back thereof is straight or approximately so in longitudinal section. In the form of construction shown the blade *c* is cut from the material of the body and handle part *b*, and is stamped or pressed into the desired form and this produces a corresponding aperture *b*³ in the body and handle part. The side edges *c*² of the blade are preferably curved inwardly slightly adjacent to the point *c*³ thereof as shown at *c*⁴, but this curve of the side edges *c*² of the blade is not an absolutely essential feature, and it will be understood that the side edges *c*² are cutting edges and the point *c*³ is so formed as to be easily forced through the head *a*² of the can when the opener is placed horizontally thereover.

The handle end portion of the body of the opener is preferably provided, at a predetermined distance from the blade *c* with a prong *d* the object of which is to produce a vent opening *e* in the head of the can when the opener is manipulated as hereinafter described, and in the handle end portion *b*² of the body part of the device is preferably formed an aperture *b*⁴ whereby the device may be suspended from a hook or other support when not in use.

In the operation of this form of my improved can opener the said implement is placed on the top or head of the can, in the position shown in Fig. 1, with the point *c*³ of the blade resting on said head of the can adjacent to one rim thereof and the body or handle portion of the opener extending diametrically across said head. With one hand used in supporting the opener in this position the other hand is used for forcing the blade *c* and prong *d* downwardly through the head of the can, as clearly shown in Fig. 1, after which, while the end *b*³ of the body part of the device is held firmly in the position shown in Fig. 1, the other end

portion thereof is raised and swung backwardly in a plane passing centrally and vertically through the can. The result of the first step of this operation is shown in Fig. 3, and the result of the second step is shown in Fig. 4, and from these figures it will be seen that the operation of forcing the blade *c* downwardly through the head of the can forms a crescent shaped aperture *a*³ therein, 10 and at the same time cuts out a tongue portion of said head which is shown at *a*⁴ and which is bent downwardly, and the second step of this operation produces a semi-circular or an approximately semi-circular aperture *a*⁵, the tongue portion *a*⁴ being bent 15 backwardly under the head *a*² of the can by the pointed end portion of the blade *c* when the handle portion of the opener is moved backwardly as described. With the 20 aperture *a*⁵ in the head of the can and the vent *e* to permit air to enter the can the contents thereof may be freely discharged through said aperture, as will be readily understood, and my invention is not limited 25 to the use of the prong *d*, the vent being only to facilitate the discharge of the contents of the can, which operation might also be facilitated by enlarging the aperture *a*⁵ or changing the form thereof.

30 Having fully described my invention what

I claim as new and desire to secure by Letters Patent is;—

A can opener comprising a main body or handle portion provided at one side and adjacent to one end with a blade which projects 35 at right angles thereto, said blade being of crescent form in cross section and the side edges thereof being convergent to a central point, said blade being widest at the handle or body portion, and said handle or body 40 portion being provided back of the blade with a projecting member which forms a stop to limit the distance the blade can be forced into a can, and which also forms a fulcrum on which the body or handle portion is turned backwardly after the blade is forced downwardly through the head of the can, and said handle being also provided with a prong adapted to form a vent in the 45 head of the can when the blade is forced 50 thereinto.

In testimony that I claim the foregoing as my invention I have signed my name in presence of the subscribing witnesses this 18th day of March 1912.

JAMES M. PURDY.
